HEAD REST REPRODUCER

Albert K. Ward, Audubon, N. J., assignor to
Radio Corporation of America, a corporation
of Delaware

Application June 17, 1932, Serial No. 617,797

3 Claims. (Cl. 179—182)

My present invention relates to reproducers, and more particularly to a head rest reproducer adapted for operative positioning between the head and shoulder of the listener.

5 In centralized radio systems, especially used in hospitals, it is often desired to localize reproduction with respect to each listener. So-called "radio pillows" have been provided for this purpose, such devices comprising a pillow made of 10 sponge rubber, a telephone reproducer being disposed at the center of the pillow. An invalid or a well person could thus recline in bed, and position an ear upon the pillow, radio reception thus being individualized in a comfortable manner. 15 However, there are numerous instances in hospitals, and other places, where it is undesirable, impossible or troublesome to utilize a radio pillow device. There are many cases, for example, where it is required that individuals rest on their backs, and not move around. This position may 20 be enforced or voluntary; but, in either case, a radio pillow device is not as convenient and desirable as a head rest reproducer.

Therefore, it may be stated that it is one of 25 the main objects of this invention to provide an improved type of individual reproducer, wherein the electrical reproducer is disposed within a sponge rubber, or other resilient housing, the latter being of such dimensions and shape that it may be readily disposed between the ear of a 30 person and the adjacent shoulder in non-slipping position.

Another important object of the invention is 35 to provide a radio reproducer device comprising a sponge rubber housing having a base of a relatively large area, the base being adapted to rest on the listener's shoulder, and a face designed to rest against a side of the listener's head, said face being provided with an orifice shaped to receive the ear of the listener, there being an electrical telephone within the housing.

40 Other objects of the invention are to improve generally the simplicity and efficiency of individual radio reproducers, and to particularly provide a device or apparatus of the present type which is not only economical, durable and reliable in operation, but economically manufactured.

45 The novel features which I believe to be characteristic of my invention are set forth in particularity in the appended claims, the invention itself, however, as to both its organization and method of operation will best be understood by reference to the following description taken in connection with the drawing in which I have in-

5 dicated diagrammatically several elements whereby my invention may be carried into effect.

In the drawing,

Fig. 1 shows a side elevation of the present invention. 5

Fig. 2 shows a plan view of the device of Fig. 1. Fig. 3 is a front elevation of the device shown in Fig. 1 looking in the direction of the reproducer orifice.

Referring now to the accompanying drawing 10 wherein like reference characters designate the same elements in the different views, Fig. 1 shows the appearance of the device viewed from the side. The base 1 is preferably made flat or plane and of a relatively large area, and is 15 square in shape as can be seen by reference to Fig. 2. Actually it may be about five and one-half inches square. Fig. 3 shows the appearance of the device from the orifice 2, the top portion of the face 3 being arcuate in shape. 20

It will be noted that the face 3 is rearwardly inclined (see Fig. 1) and curves backwards above the orifice 2. The height of the device is about six inches. The rear face 4 comprises a reinforcing, or buttress, portion 5, the top of the buttress tapering towards the top of face 3 in a double curve. Thus, it will be seen that in general the device is triangular in cross section; when sectioned vertically through the orifice 2, the rear of the triangle base being extended to provide 30 a buttress. 25

The face 4 is provided with an aperture 6 of a bore 7, the opposite opening of the bore 7 being designated by the numeral 8. The electrical reproducer, or telephone, 9 is disposed within the chamber 10. This chamber is formed by cementing the front and rear portions of the housing along the line C, and providing the circular spaces 11 and 12 in the said portions. The spaces 12 and 11, when the rear and front portions are cemented, have a sound opening 13, the conical space 14 connecting the openings 13 and 2. The wire 15 connecting the telephone 9 to the centralized radio system is, of course, disposed in the bore 7. 35

The wire 15, connected from the centralized radio distribution channel to each telephone reproducer 9 will be understood to be connected in any well known manner to the reproducer 9 housed in the rubber casing, and extends through the bore 7 to the exterior and rear of the rubber 50 casing, the centralized distributing system itself being of any well known type. For example, such a system may follow the teachings of U. S. Patent 1,845,302 to L. W. Luellen. It will be noted that the connecting conical space 14 of the sound 55

outlet portion of the device includes a surface portion which is out of alignment with the remainder of the conical surface.

When viewed, as in Fig. 3, it will be seen that 5 there is thus provided a sound outlet surface which readily fits the ear of the listener. In Fig. 3 the lower portion 20 corresponds to the curved portion 20 of Fig. 1 which is out of alignment with the remainder of the conical connecting surface.

As stated heretofore, the present device is normally constructed in two parts, the cementing line C dividing, as shown in Fig. 1, the device into two portions. One of these main portions is provided with the space 12, the conical connecting space 14 and the apertures 13 and 2 as well as a substantially square shallow space 2'. The other main portion of the device is provided with the space 11, the bore 7 and a substantially square shallow space 2'' which is adapted to fit the space 2' and provide therewith a wide space, having a thickness of about an eighth of an inch between the base 1 of the device and substantially the center of the spaces 11 and 12. When the two 20 main portions of the device, pre-formed as stated heretofore, are cemented along the line C the complete device of this invention is provided.

Of course, prior to cementing along the line C, the telephone reproducer 9 has been positioned 30 in spaces 11 and 12, with its sound outlet operatively positioned with respect to the opening 13, and the wire 15 is positioned within the bore 7, with the wire projecting outwardly beyond the opening 6. After the two main portions have 35 been cemented along line C the surfaces 1, 3 and 4 of the device may have cemented thereto any desired type of ornamental coating or fabric, and it is also to be understood that such an ornamental coating is placed over the surface of the 40 conical connecting space 14 as well as a substantial portion of the bore 7.

It is believed that the manner of using the device of the present invention will be clearly understood from the above description and from 45 the drawing. It has already been pointed out how the device is constructed out of two main portions and it is believed that those skilled in the art are well acquainted with the manner of providing the various grooves and spaces within the 50 said main portions, it being understood that such spaces, grooves and bores may be provided by cutting, molding, or similar operations. When the device has been constructed and is ready for use, and assuming that program energy is being 55 delivered to the telephone reproducer 9, it is merely necessary to position the device adjacent the listener's ear. In this position the base 1 rests upon the shoulder, the aperture 20 being adjacent the ear.

60 It will be noted that in this position if the listener's head presses against the face 3, the buttress portion 5 functions to prevent the device from toppling backward away from the ear and toward the listener's arm. Due to the sponge rubber construction of the device there will be 65 no discomfort due to pressure of the ear against the orifice 2. It is to be particularly noted that the construction of the present device results in a device which is not only positioned between the shoulder and ear of a listener, but is snugly fitted in such position in such a manner that it 70 may be said that the device is wedged into position between the ear and shoulder of the listener.

A consideration of Fig. 1 will demonstrate this 75 fact, the side base 1 and the face 3 being arranged

at an angle of about 80° with each other and providing the wedge portion referred to. Hence, it may be more properly stated that the present device actually comprises an individualized reproducer which is capable of being wedged into position between the listener's shoulder and ear without causing discomfort to the listener's head or shoulder because of the resilient and sponge rubber construction of the device.

This unit, besides fitting in between the shoulder and the ear, is also built so that it may be placed flat on the sheet of the bed and be placed in such a position that it will reproduce directly into the ear in a manner similar to a book-end being pushed up close to the head. Also, all parts 15 can be cemented together before the headphone is installed. A four inch slot is left in the base of the unit for the insertion of the headpiece.

While I have indicated and described one arrangement for carrying my invention into effect, it will be apparent to one skilled in the art that my invention is by no means limited to the particular organization shown and described, but that many modifications may be made without departing from the scope of my invention as set 25 forth in the appended claims.

What I claim is:

1. In a device of the class described, a housing for a sound reproducer comprising only two mating portions each formed of a unitary mass of 30 sponge rubber, each of said portions having a circular chamber formed therein, said chambers being aligned and adapted to enclose and support the sound reproducer, one of said housing portions being formed with an outlet aperture 35 and a conical shaped portion connecting said aperture with one of said circular chambers, said housing being formed with a broad flat base which is arranged at an angle of substantially 80 degrees with the face having said outlet aperture and spaced from said sound outlet aperture by the normal distance between the shoulder and ear of a person, whereby upon resting the base on his shoulder sound waves emitted from said 40 reproducer will be directed into a listener's ear. 45

2. In combination, a housing formed of a mass of sponge rubber and provided with a hollow chamber within its interior, a telephone reproducer positioned within said chamber, a substantially conically shaped sound outlet chamber 50 formed in said rubber housing on one side thereof, said reproducer chamber and outlet chamber being connected by a common aperture, and said outlet chamber opening into one face of the housing, the last mentioned opening being enlarged to form a configuration adapted to fit a 55 listener's ear, a bore provided below said reproducer chamber and extending between it and the rear face of said housing, said bore having disposed therein a wire connected to said telephone 60 reproducer, the wire extending outside the housing, the base of said housing and the face thereof provided with the ear fitting outlet chamber opening being inclined at an angle somewhat less than 90° and providing a pair of wedge faces 65 adapted to be snugly and positively positioned between the listener's ear and shoulder and the distance between said housing base and said ear shaped outlet chamber being equal to the normal 70 distance between the shoulder and ear of a person.

3. In a device of the class described, a housing for a sound reproducer comprising only two mating portions each formed of a unitary mass of sponge rubber, each of said portions having a 75

circular chamber formed therein, said chambers being aligned and adapted to enclose and support the sound reproducer, one of said housing portions being formed with an outlet aperture on its front face and a conical shaped portion connecting said aperture with one of said circular chambers, said housing being formed with a broad flat base which is spaced from said sound outlet aperture by the normal distance between the

shoulder and ear of a person and said housing being further provided with an aperture extending from said circular chamber through the base of said housing and of a width greater than the diameter of said circular chamber whereby the sound reproducer may be inserted from the base through said last named aperture.

5

ALBERT K. WARD.
